(57) **CLAIM**

The ornamental design for a billiards showroom divider, as shown and described.

DESCRIPTION

FIG. 1 is a perspective view of a billiards showroom divider, showing my new design;

FIG. 2 is a front elevational view thereof, wherein the rear elevational view is identical;

FIG. 3 is a top plan view;

FIG. 4 is a left-hand side elevational, wherein the right-hand side elevational view is identical; and,

FIG. 5 is a vertical cross-sectional view thereof.
